UNITED STATES PATENT OFFICE.

MIKE TODORUK, OF RUSSELL, MANITOBA, CANADA.

AUTOMATIC GATE.

1,405,464.

Specification of Letters Patent.

Patented Feb. 7, 1922.

Application filed October 6, 1920. Serial No. 414,884.

To all whom it may concern:

Be it known that I, MIKE TODORUK, a citizen of Ukraine, residing at Russell, in the Province of Manitoba and Dominion 5 of Canada, have invented certain new and useful Improvements in Automatic Gates, of which the following is a specification.

This invention relates to certain new and useful improvements in automatic gates especially designed as a farm gate that is 10 adapted for automatic operation by a vehicle passing in the direction thereof.

A further object of the invention is to provide an automatically operated fence gate 15 having trip devices arranged at opposite sides thereof adapted for operation by a vehicle to effect the automatic opening of the gate with the gate retained in open position during passage of the vehicle therethrough, the gate 20 being released for closing movement by the vehicle and gaging the other trip device at the opposite side of the gate.

With the above and other objects in view, the present invention consists in the novel 25 form, combination and arrangement of parts hereinafter more fully described and shown in the accompanying drawings, in which like reference characters indicate similar parts throughout the several views.

30 In the drawings,

Figure 1 is a top plan view of an automatic fence gate constructed in accordance with the present invention showing the gate in its closed position,

35 Figure 2 is a vertical longitudinal sectional view taken on line II—II of Figure 1 showing the tensioned slidable latch operating arm for retaining the gate in open position,

40 Figure 3 is a detail sectional view taken on line III—III of Figure 2 showing the sliding operating arm for the gate latch,

Figure 4 is a longitudinal sectional view of one of the gate operating trips,

45 Figure 5 is a horizontal sectional view taken on line V—V of Figure 7,

Figure 6 is an end elevational view, partly in section of one of the gate operating trips, and

50 Figure 7 is a fragmentary detail elevational view of a portion of the gate and the latch for retaining the same in closed position.

Briefly described, the present invention 55 has for its main object to provide a fence gate that is automatic in operation and de-

signed to be opened and closed by the action of a vehicle engaging trip devices at opposite sides thereof. An overbalanced retaining latch is adapted to engage a keeper carried by the swinging end of the gate for retaining the same in closed position, the latch having cord connections with each trip device whereby the operation of either of the trip devices releases the latch from the gate 60 keeper to permit the gate to swing to an open position against spring tension and so retained. The trip devices have cord connections with the bearing of the swinging gate so that when the latch for retaining the gate in closed position is released from the gate keeper, the gate will be positively 65 swung against the spring tension thereon to an open position for engagement with a keeper latch positioned laterally of the roadway through the gate opening, thereby retaining the gate in its open position and against the spring tension thereon. The cords for effecting the opening movement 70 of the gate are interconnected and attached to a sliding operating arm for releasing the latch from the gate keeper whereby the operation of either of the trips effects the opening and closing movement of the gate.

Referring more in detail to the accompanying drawings, and particularly to the device as illustrated in Figure 1, there is 75 illustrated an automatically operated swinging fence gate 10 mounted on a vertical pivot 11 in the wall 12 of the laterally positioned longitudinally extending casing 13. Trip devices 14 and 15 are arranged respectively, at opposite sides of the gate 10 and are aligned with the roadway 16 closed by the gate 10, the trip devices having cord connections with the swinging gate 10, a keeper latch 17 for retaining the gate in closed position and a keeper latch mechanism 18 for retaining the gate in open position as shown by dotted lines in Figure 1. While the connections between the trip devices, the gate and the latch devices are referred to as cords, it is to be understood that any form of connection such as chains or wires, may be employed.

The gate 10 is journaled at its upper end as at 19 in the top wall of the housing 20 that is mounted on the lower housing 13, the lower hinged end of the gate carrying a disk 21 having one end of a coil spring 22 secured thereto with the other end of the spring anchored within the housing 13 as at

23, to place the gate under tension for normally holding the same in its closed position. When the gate is in closed position extending across the roadway 16 as shown in 5 Figures 1 and 7, the keeper mechanism 17 embodying a vertical standard 24 has an overbalanced lever latch 25 pivoted thereto as at 26 with the forwardly projecting end of the latch 25 positioned for engagement 10 with the beveled keeper lug 27 carried by one face of the gate 10, the spring 22 moving the gate to its closed position and causing the lever latch 25 to ride over the beveled nose of the keeper lug 27.

15 In order to effect an opening movement of the gate against the tension of the spring 22, the trip devices 14 and 15 as above described are positioned at opposite sides of the gate and have cord connections with the disk 21 20 associated with the gate hinge. These cord connections are more clearly shown in Figure 1, the same extending from the trip devices to the housing 13 and interconnected therein, the operating cord for the gate extending from the trip device 15 being designated by the reference character —a— as 25 passing through the opening 28 in the wall 12 of the housing 13 and traversing the bracket supported pulley 29 as shown in said figure and further passes over the bracket supported pulley 30 with the portion designated —b— attached to the gate disk 21. The cord intermediate the pulleys 29 and 30 has connected thereto as at a' a cord —c— 30 that extends to the opposite end of the housing 13 for passage over the bracket supported pulley 31 and the end —d— of the cord —c— yet the pulley 31 is attached to the latch mechanism that holds the gate in 35 open position to be later described, and as shown in Figure 2. It will therefore be seen that the operating cord extending from the trip is connected to the gate for moving the same to open position and also is connected to the latch mechanism for releasing the gate from its open position.

A similar cord arrangement extends from the trip device 14 to the gate 10 and gate releasing latch mechanism 18, the same being 40 designated by the reference numeral 1 as entering the opening 32 in the wall 12 of the housing 13 and passes over the bracket supported pulley 33 and continues as indicated by the reference numeral 2 for passage 45 over the bracket supported pulley 34, and further passes over the bracket supported pulley 35 and reversely travels as indicated by the numeral 3 for connection as at 2' with the cord section —c—. A cord 4 is connected as at 4' to the cord section 2 and passes over the bracket supported pulley 36 with the free end 5 thereof secured to the disk 21 of the gate. Similar to the cord connection —a— between the trip devices 15 50 and the gate 10 and latch mechanism 18, is

the cord connection —l—. The cord —l— entering the housing 13 and passing over the several pulleys as above described is attached to the disk 21 of the gate and to the cord —c— having the free end —d— thereof extending to the gate latch mechanism.

The latch mechanism 18 for retaining the gate 10 in its open position against the tension of the spring 22 is shown more clearly in Figures 2 and 3, a guide bar 37 being rigidly supported within the superposed housing 20 in inclined relations having a longitudinal key slot 38 in which the interlocking arm 39 is slidably mounted. A lug 40 depends from the arm 39 and passes through a slot 41 in the lower face of the guide bar 37 and to which the free end of the cord section —d— is attached as shown in Figure 2, the cord passing through the opening 13' in the top wall of the housing 13. A coil spring 42 is attached at one of its ends to the housing 13 and at its other end to the cord section —d—, thereby placing all of the cord sections under proper tension. In order to hold the sliding latch operating arm 39 at its limit of movement in one direction, the spring 43 is connected at one end to the outer end of the bar 37 and has its other end connected to the lug 40 as clearly shown in Figures 2 and 3, the springs 42 and 43 maintaining the cord sections and sliding arm properly positioned. As shown in Figure 2, a block 44 is carried by the outer end of the sliding arm 39 and has pivoted thereto one end of a latch operating arm 45, a wire spring 46 being interposed between the arms 39 and 45 for maintaining the pivoted arm 45 resiliently elevated and limited by the strap guide frame 47. A latch casing 48 is secured to the inner wall of the housing 20 and has the nose 49 of the sliding latch bolt extending from the latch casing into the opening 20' in the housing 20, a ring 50 carried by the sliding bolt extending through a slot in the casing 49 and into which ring the free end 51 of the pivoted arm 45 resiliently extends.

The trip devices 14 and 15 being of similar construction are shown in detail in Figures 4, 5 and 6, a platform 52 being placed in the roadbed 16 at each side of the gate 10 and carrying a pair of depending vertically slotted guide bars 53 between which a vertically slidable board 54 is resiliently mounted, guide pins 55 being carried by the lower ends of the guide bars 53 and extending into slots 56 formed in the lower end of the board 54 while coil springs 57 surround the guide rods 55 between the lower ends of the bars 53 and the board 54 thereby resiliently supporting the trip boards 54. As shown in Figures 4 and 6, the trip boards 54 extend upwardly through slots 58 in the platform 52 and the meeting edges of trip boards 59 rest on the upper projecting end thereof, the 130

trip boards 59 being anchored to the platform 52 by the spikes 60 entering the platform through slots 61 in the platform boards 59. A supporting frame 62 depends from the 5 platform 52 and a pair of pulleys 63 and 64 journaled therein. As shown more clearly in Figures 4 and 5, a lever 65 is pivoted as at 66 to the lower end of the board 54 and a link rod 67 depending from the guide bar 10 53 has the lower headed end 67' thereof constituting a pivotal mounting for the lever 65, the free end of the lever as shown in Figure 6 being provided with an opening 68 for the reception of the free end of either 15 of the cords —a— or —b—. To effect the release of the latch lever 25 from the keeper lug 27 simultaneously with the shifting of the gate operating cords, a lever 69 is pivoted as at 70 to the edge of each board 54 20 and has one end thereof positioned for engagement with the standard pin 71 upon the guide bar 53 while the other end of the lever has a cord connection 72 which cords 72 from the separate trip devices 14 and 15 pass 25 over sheaves 73 secured to the lower end of the standard 24 for engagement as at 74 with the free end of the lever latch 25.

Assuming that the gate is in the closed full line position shown in Figure 1 and it 30 being desired to swing the gate upon its hinged mounting 11 as indicated by the arcuate line 10' in Figure 1, the weight of a vehicle upon either of the platform boards 59 will depress the vertically sliding board 35 54 operating the lever 69 to release the lever latch 25 from the keeper lug 27. Simultaneously with this movement, the lever 65 will move upon its pivotal connection 67' with the hanger 67 to elevate the end thereof 40 connected to the cord —a—, moving the cord over the pulleys 64 and 63 and by the cord connection —b— with the disk 21 of the gate will swing the gate against the tension of the spring 22 to position the keeper 49' carried by the swinging end of the gate 10 in the opening 20' of the housing 20 for engagement with the latch bolt 49, thus retaining the gate in its open position against the tension of the spring 22. The over- 45 balancing of the lever latch 25 will retrieve the slack in the cords 72 and present itself for engagement by the keeper lug on the gate 10 when again closed. After a vehicle has passed through the gate opening the 50 other trip device is operated and through the cord connections —a— to —d— with the sliding arm 39, said arm is moved in the guide bar 37 to cause the pivoted arm 45 to shift the latch bolt 49, thereby freeing 55 the latch bolt from engagement with the 60

keeper 49' upon the swinging gate 10 to permit the spring 22 to return the gate to its closed position with the keeper lug 27 upon the opposite face of the gate again engaging the lever latch 25. It will therefore be 65 seen that the forcible lowering of the vertically sliding boards 54 against the supporting springs 55 will effect a positive rotation of the gate upon its hinge mounting 11 against the tension of the spring 22 and 70 present the keeper 49' carried thereby for engagement by the latch bolt 49, and also, that a subsequent operation of either of the trip devices will effect the operation of the latch bolt 49 to disengage the same from 75 the keeper 49' carried by the gate whereupon the spring 22 will return the gate to its closed position. While there is herein shown and described what is believed to be the preferable embodiment of the invention, it is nevertheless to be understood that minor changes may be made therein without departing from the spirit and scope of the invention as claimed.

What is claimed as new is: 80

1. Gate operating mechanism comprising a swinging gate, independent means for holding the gate in open and closed position, a trip device arranged at each side of the gate, cord connections between the trip devices and the gate adapted upon operation of the trip devices to positively move the gate to open position for engagement by the holding device, means operated by the trip devices for releasing the means for holding the gate in closed position, the device for holding the gate in open position comprising a sliding latch, and a shiftable arm connected to said latch and operated by the connecting cords. 90

2. Gate operating mechanism comprising a swinging gate, independent means for holding the gate in open and closed position, a trip device arranged at each side of the gate, cord connections between the trip devices and the gate adapted upon operation of the trip devices to positively move the gate to open position for engagement by the holding device, means operated by the trip devices for releasing the means for holding the gate in closed position, the device for holding the gate in open position comprising a sliding latch, a shiftable arm connected to said latch and operated by the connecting cords, and means for resiliently holding the shifting arm in engagement with the sliding latch. 105

In testimony whereof I affix my signature.

MIKE TODORUK.
